[57] CLAIM

The ornamental design for water distilling apparatus, as shown and described.

DESCRIPTION

FIG. 1 is a perspective view of water distilling apparatus showing my new design;

FIG. 2 is a front elevational view thereof;

FIG. 3 is a top plan view thereof;

FIG. 4 is a side elevational view thereof;

FIG. 5 is a rear elevational view thereof.

The broken line drawing of the water conditioning and pump components in FIGS. 3, 4 are shown for illustrative purposes only and forms no part of the claimed design. The oblique line shading on the top portion of the distiller represents a translucent surface.
